United States Patent Office

Des. 178,767

Patented Sept. 18, 1956

178,767

OBJECTIVE LENS MOUNTING

Charles J. De Grave, Jr., Chili, N. Y., assignor to Bausch & Lomb Optical Company, Rochester, N. Y., a corporation of New York

Application April 15, 1955, Serial No. 35,535

Term of patent 14 years

(Cl. D61—2)

FIG. 1

FIG. 2

FIG. 3

Fig. 1 is a side elevational view of an objective lens mounting showing my new design.

Figs. 2 and 3 are end views thereof as seen, respectively, from the left and right sides of Fig. 1.

I claim:

The ornamental design for an objective lens mounting, substantially as shown.
